UNITED STATES PATENT OFFICE

STEFAN SCHVACHO, OF TRENCIANSKE TEPLICE LAZNE, CZECHOSLOVAKIA

SOCKET FOR THE COMBINATION X-RAY RADIATORS

Application filed October 29, 1927. Serial No. 229,694.

The object of this invention is the improvement of all the well known medical radiating apparatuses where the fundamental part is a socket for the combination X ray radiator, which serves for different medical purposes, as X ray generator quartz lamp, Solus lamp, Finsen and electromagnetic lamp. With the help and due to the arrangement of this socket, the different above mentioned radiating lamps may be used for various medical purposes.

The usefulness of the apparatus lies in the fact that it can be used for various medical purposes, therapeutic and diagnostic. It is simple and easy to operate same by only changing the required radiating lamp or tube, for instance: Removing the X ray lamp and replacing same with the quartz sun lamp the apparatus will function as quartz lamp producing ultra-violet-ray etc.

The combination X ray radiator socket is shown through different views. Fig. 1 longitudinal section of socket, Fig. 2 cross-section of socket, Fig. 3 socket in closed position.

The socket was made for the aforementioned purposes, and is constructed of any good insulating material made in the shape of globe (1) in two parts, and serves as a socket into which the various lamps may be inserted.

This insulating globe (1) of two parts is provided with two extending arm channels, which serve as supports for the extending arms of all the clamps. For opening and closing this double insulating globe (1), hinges (4) were provided. And to lock the globe a key-hinge lock (5) is used.

This double insulating globe (1) is fastened on a moving arm (7). The extending arm channels (2) have end snap-locks (8), so as to hold the extending lamps fast in place. The extending arm channels (2) are made of insulating material. The end snap-locks (8) are provided with proper hinges (11) and with a lock-key (12). Furthermore, this double insulating globe (1) is equipped with a reflecting camera (13), which has a lamellated shutter mechanism (14), controlled by a regulating screw (15)

and the opening to the reflecting chamber may be made small or large as desired.

Claims

1. A radio-therapeutic device of the character described, comprising a globe shaped casing constituting a lamp socket formed in two concentric sections and provided with a plurality of tubular arms for the insertion of lamps of different characters, said arms being provided with locking means for the lamp.

2. A radio-therapeutic apparatus as recited in claim 1, in which the globe shaped socket is equipped with hinge and locking means, and is provided with a reflecting chamber and with a shutter and shutter regulating means.
